UNITED STATES PATENT OFFICE.

HERMANN MERKEL, OF ST. LOUIS, MISSOURI.

DESIGN FOR A HYDROCARBON-BURNER.

SPECIFICATION forming part of Design No. 32,106, dated January 16, 1900.

Application filed November 13, 1899. Serial No. 736,877. Term of patent 7 years.

To all whom it may concern:

Be it known that I, HERMANN MERKEL, a citizen of the United States, residing in the city of St. Louis, State of Missouri, have invented and produced a new and original Design for a Hydrocarbon-Burner, of which the following is a specification.

Figure I is a side elevation of a hydrocarbon-burner embodying my new design. Fig. II is a top plan view.

As shown in the drawings, the leading or essential feature of my new design for a hydrocarbon-burner consists of the cylindrical portion 1, having the vertical central opening 2, the rectangular recesses 3 in its outer face, the ribs 4 between the recesses, and the openings 5, extending from the upper end of the cylinder down into the recesses, thus connect-

ing the recesses with the opening 2, the upper end of the opening 2 being enlarged to form the shoulders 6, and the cylindrical portion 7, extending downwardly from the portion 1 and having the horizontal openings 8, communicating with the opening 2, said portion 7 being smaller than the portion 1. A bead 9 marks the junction of the portions 1 and 7, and the bead 10 and the rounded portion 11 appear at the lower end of the portion 7.

I claim—

The design for a hydrocarbon-burner, substantially as herein shown and described.

HERMANN MERKEL.

Witnesses:

M. LOUISE HOOVER,
SEMER G. WELLS.
